UNITED STATES PATENT OFFICE

2,641,436

AUTOMATIC WEIGHER

Herman Schmid and Albert P. Hobush, Kingston,
N. Y., assignors to Incoro, Inc., Kingston, N. Y.,
a corporation of New York

Application December 16, 1949, Serial No. 133,426

1 Claim. (Cl. 249—60)

1

This invention is an improved dispensing apparatus; and especially a dispensing apparatus for delivering prepared material in predetermined quantities by weight.

An important object of this invention is to provide a supporting member for a receptacle into which an admeasured quantity of the material is delivered, and means actuated by the weight of the contents of the receptacle for stopping the production and delivery of the material as soon as the desired amount thereof has been deposited in the receptacle.

A further object is to provide a supporting member to serve as an adjunct to a machine by which said material is processed, and which is operated by a power unit such as an electric motor; said member having connections which are operated to interrupt the circuit of the motor and stop the machine when the weight of the receptacle and its contents displaces said member.

Another object is to provide the supporting member with counterweighting means which is overbalanced by the weight of the contents of the receptacle to open the motor circuit as soon as the required amount of material has been delivered to said receptacle.

Other objects and the advantages of the improvement are clearly set forth in the ensuing description; and the novel features are pointed out in the claim. The drawings illustrate the best form of the invention now known to us, but changes in shape, size and arrangement of parts can of course be made without really altering the essential construction in which the invention is embodied.

On said drawings:

Figure 1 is a front view of apparatus constructed in accordance with this invention, showing all but the top.

Figure 2 is a detail in section, taken along the line 2—2 on Figure 1.

Figure 3 is a longitudinal section along line 3—3 on Figure 1;

Figure 4 is an elevation of the panel bearing the indicating means.

Figure 5 is a transverse horizontal section along line 5—5 on Figure 4;

Figure 6 is a horizontal section on line 6—6 in Figure 3, and Figure 7 shows the electrical circuit for operating and controlling the apparatus.

The apparatus comprises a housing 1, standing upon a base 2. The machine for processing the material is indicated at 3, and is operated by an electric motor 4. The machine 3 is adapted to grind coffee, which it receives from a hopper or

2

bin 5 at the upper part of the housing, this hopper having a bottom 6 with inclined sides, all converging to an outlet opening 7 above the machine 3. After being ground in the manner required, the coffee is discharged through a chute or spout 8 into a receptacle, such as an ordinary paper bag 9, resting on a supporting member or plate 10. A counterweight 11 holds the plate 10 in position while the ground coffee is discharged into the bag 9 by the spout 8; but as soon as the contents of the bag attain the predetermined weight they overbalance the counterweight 11 and cause it to rise. This action, as will presently be explained, causes a switch in the electric supply circuit of the motor to open, so that the operation of the motor and of the grinder at once ceases. The counterweight 11 can be adjusted if desired, so that the bag 9 will receive one pound, two pounds or a different quantity of ground coffee before the grinder is stopped.

The front of the casing 1 and base 2 has a recess 12 in which the plate 10 is disposed. The plate is carried by a rocking seat or frame consisting mainly of two L-shaped arms 13 pivotally mounted in fixed uprights 14 on the base 2. The parts of the angle-shaped arms 13 in the recess 12 under the plate 10 are substantially horizontal, and the parts between the posts 14 are vertical. The arms 13 have horizontal extensions 15 projecting to the rear of the posts 14 and united at their ends by a cross bar 16. The junctions of the extensions 15 and the vertical portions of the arms 13 are united by a cross shaft 17 having a longitudinal bore to receive a fixed pin 18 projecting at both ends from the shaft 17. The extremities 19 of the pin 18 are triangular in shape, with the apex of each pointing downward and engaging notches or recesses in projections 20 on the inner faces of the posts 14. The seat for the plate 10 made up of the arms 13, with extensions 15, is thus suspended between the posts 14 in knife edge bearings. Also the front ends of the arms 13 are spanned by a cross bar 21 with similar triangular ends 19, each having an apex at the top. The ends 19 of the bar 21 fit into triangular notches on projections 22 affixed under the lower face of the plate 10 at the ends of the latter. Thus the plate 10 is mounted by means of knife edge bearings in the frame carrying it. The plate has hook-shaped stops 23 beneath it and under the arms 13, and fixed upright arms 24 at the two sides and back, and the arms 24 at the sides of the plate are connected by pivoted links 25 to the upright posts 14. To the cross bar 15 is affixed a rearward extending rod or

shank 26 bearing the counterweight 11. This arm is preferably threaded to permit the weight to be adjusted, and it may be locked in place by an ordinary binding screw 27.

By means of the angle-shaped arms 13 with horizontal portions under the support 10, and vertical portions pivotally attached at their upper ends to the posts 14, and the links 25 of proper length pinned to the upright arms 24 and to the posts 14 above the vertical portions of the arms 13, the member or plate 10 is maintained horizontal when the arms 13 are depressed and all risk of tipping the receptacle on the plate 10 and spilling the contents is obviated.

Secured to the back of the uprights 14 above the extensions 15 is a switch casing 28 which contains a switch in the circuit of the motor 4, part of which is indicated at 29. One of the extensions 15 bears a projection 30 on top. This projection is out of operative position when the member 11 is down, but when the plate 10 sinks under the weight of the coffee in the bag 9, the part 30 will open the switch and break the motor circuit. The grinding and delivery of the coffee will then stop. The switch device in the casing 28 is not the main switch, which as Figure 7 shows is of course mounted within convenient reach, so that the motor circuit will be closed only when a bag 9 is stood on the plate 10 to be filled.

The posts 14 also carry stop screws 31 to engage the vertical parts of the arms 13, for adjustment of said arms. In the base 2 a plate 32 closes the bottom of the recess 12.

The motor casing is conveniently suspended in the housing 1 by a metal strap or sling 33 which is affixed at its ends to projections 34 on the lower side of the bottom 6 of the bin 5. The top of the housing has an opening 35, through which the bin or hopper can be charged with the roasted coffee beans to be ground and this opening is closed by a lid 36 having a knob 37 for handling. The front and back of the housing have windows closed by transparent panes 38, so that the level of the coffee in the bin can be watched.

The grinder 3 is not part of this invention and is constructed to deliver the coffee ground in any one of the usual four ways, to serve as regular or coarsely ground coffee, powdered coffee, drip coffee or percolator coffee. For this purpose the grinder has a rotatable knob 39 in front to set the machine to deliver the kind of ground coffee ground in any one of the four ways mentioned, as each customer may desire. The knob carries a block of insulation 40, at the end of a fixed arm 41. The arm projects upward and the insulator 40 bears on its inner face a conductor strip 42 with overturned ends. This strip cooperates with four pairs of terminals 43 on the outer face of the front of the housing and bridges each pair to close separate circuits by which the manner of grinding is controlled. The terminals 43 are heads on the ends of bolts 44 to which the conductors of the controlling circuits are united. The front of the housing is made of plastic or some other insulating substance and the bolts 44 are carried by blocks of insulation 45, secured by the bolts in position on the housing 1, see Figure 2.

At the rear the apparatus carries means for indicating the kind of coffee which is being ground and delivered, according to the setting of the grinder and motor by the head 39. The back of the housing has an opening closed by a

frame 46 holding a transparent pane 47 on its inner face. This frame has intersecting bars 48 dividing it into four windows. Over the inner face of the frame is secured a sheet or frame of metal 49 with a central opening 50, the edges of which overlap the pane 48 and hold it in place. This sheet has intersecting ribs 51 inside the housing registering with the bars 48 so as to form four open sections, each for a different illuminating lamp. At the ends of the plate 49 each section or compartment has a clip 52 affixed to its edge and carrying a lamp socket 53. The separate lamps or indicator members in the sockets 53 are shown at 54, with supply wires 55. The lamps are so connected that each is in circuit with a different pair of terminals 43. Hence each lamp will be illuminated when the corresponding circuit is closed, and the operator can tell whether the grinding is being done in the manner ordered. On the glass 47 words may be inscribed over each of the lamps to inform the operator whether regular ground coffee, powdered coffee or drip or percolator coffee is being produced. The sheet 49 is attached by screws 56, engaging the frame 46. The switch casing 28 can be mounted on the posts 14 by a cross bar 57. Stops 58 on the outside of the housing 1 limit the movement of the knob 39, and the bottom of the bin 5 has a projection 60 with a flat end, forming a seat 61 against which the motor is held by the strap 33.

The stops 23 are the ends of a bar 62 bent downwardly towards each other. The bar 62 is affixed to the under side of a bar 63 made fast to the lower face of the plate 10 and these stops 23 prevent the lateral displacement of the plate from the rocking seat carrying it. The seats 22 for the knife edge bearing elements 19 on the arms 13 are secured with the corners of the bar 63 on strip 62 under the plate 10.

The circuit for the motor 4 is illustrated in Figure 7. The switch in the casing 28 operated by the rocking seat comprises a movable blade 64 and a fixed terminal 65, the former being actuated by the projection 30 when the counterweight 11 rises. The leads of the circuit are attached to a connector plug 66 which can be inserted into an ordinary outlet for the light and power circuit of a building. The circuit also has a hand-operated switch 67; the motor, the switch 67 and the switch actuated by the rocking seat all being in series. In parallel with the two switches aforesaid is a third switch having a movable blade 68 and a fixed terminal 69; and bridging the circuit at a point between the switch actuated by the rocking seat and the main switch 67 on one side, and a point between the motor and the plug 66 on the other, is a magnet coil 70. The switch terminals 64 and 65 are normally in contact, but the switch 67 is normally open. It can be closed by pressure, but immediately opens when released. The switch blade 68 is held open by a spring that need not be shown herein.

To use the apparatus, the attendant presses the button or knob of the switch 67 and then releases it. The circuit is thus closed and current flows through the coil 70 and pulls the blade 68 down into contact with the fixed terminal 69. The terminals of the switch 67 are now separated, but current flows through the terminal 68 and 69, and the terminals 64 and 65 till the plate 10 is depressed and the weight 11 is lifted. The circuit is then broken by the projection 30 and the terminals 68 and 69 open. Because the

switch 67 will open at once when released, there is no risk of the circuit being closed except during the grinding process.

Each of the lamps 54 is of course in series with the right pairs of terminals 53 to indicate correctly the manner in which the grinder is operating.

The invention is thus well calculated to give the objects in view. The apparatus is effective and certain in operation, but relatively simple, 10 and not likely to get out of order.

Having described our invention what we believe to be new is:

Apparatus for feeding prepared material from a machine having a housing with a feed chute 15 and a motor to operate the machine, said apparatus comprising a supporting member adjacent the chute for a receptacle, angle-shaped arms each having a horizontal portion under said member, bearings on said portions and said 20 member for movably mounting said member on said portions, said arms also having vertical portions, vertical posts at the sides of said member adjacent said vertical portions, a pin supported by said posts and engaging said vertical portions 25

for pivotally mounting said arms on said posts, upright arms affixed to said member and extending above said member, links pivotally connecting said upright arms to said posts above said 5 pin, an adjustable counterweight, a horizontal shank rigid with said angle-shaped arms, carrying said adjustable counterweight, and a switch device on said posts controlled by the movement of said angle-shaped arms to stop the motor and machine when a predetermined quantity of said material has been delivered to said receptacle.

HERMAN SCHMID.
